PORTABLE LAUNDRY BASKET AND
FOLDABLE SUPPORT THEREFORGordon J. Agnew, Parma, and Willard J.
Russell, Sr., Seven Hills Village, Ohio

Application May 8, 1948, Serial No. 25,848

8 Claims. (Cl. 217—122)

1

This invention relates to laundry baskets and particularly to a portable laundry basket having an improved foldable support therefor.

The primary object of this invention is to provide a portable laundry basket, having a foldable support, whose legs can be extended or retracted while holding the basket by its handles in the normal way.

Another object is to provide a device of the type stated whose legs are securely locked when in their folded or closed condition, thereby preventing any dangling or up and down sway of the legs.

A further object is to provide a portable laundry basket having a foldable support whose controls for extending and retracting its legs work with such ease that the average woman will have the strength and required grip to control the legs while holding the basket by its regular handles.

Still another object is to provide a device of the type stated that is rugged in structure and economical to manufacture.

These and other objects of the invention will become apparent from a reading of the following specification and claims together with the accompanying drawings in which like parts are referred to and indicated by like reference characters and wherein:

Figure 1 is a side elevation of the laundry basket showing the legs in their open condition;

Figure 2 is a side elevation of the same showing the legs in their closed condition;

Figure 3 is an enlarged view of a portion of the support member showing one of the cleats in alternate open and closed conditions;

Figure 4 is a left end view showing the position of the closing and opening means when the legs are in their open condition;

Figure 5 is a left end view showing the position of the closing and opening means when the legs are in their closed condition;

Figure 6 is a bottom view of the device showing the legs in their open condition;

Figure 7 is a bottom view of the device showing the legs in their closed condition.

Referring to the drawings there is shown a portable laundry basket made in accordance with this invention. Reference character 10 indicates a clothes basket of conventional construction having side portions 11, end portions 12, handles 13 and a base 14. The basket is supported by four legs 28 which are hingedly joined to the base 14 through two transversely extending cleats 20.

Each cleat 20 is substantially rectangular in

2

cross section and has three parallel edges 21, 22 and 23 as is most clearly shown in the Figure 3.

Each cleat 20 is located on the under side of the base 14 proximate the end portion 12 and is secured in place by hinges 25 which are mounted at the first edge 21 of the cleat. If desired this may be done by using a simple long hinge of the piano type instead of the two short hinges shown. The cleats can be swung to take positions which for the purpose of this specification are termed closed and open. When in their closed positions or conditions the cleats are dependent from the base as designated by the reference character 20a and when in their open positions or conditions they underlie the base as designated by the reference character 20.

Each cleat 20 has a pair of legs 28 mounted perpendicular to the lower surface thereof when the cleats 20 are in their open condition as shown in the Figures 1, 3, 4 and 6. Thus each set of legs may be folded to underlie the base 14 as designated by the reference character 28a when in their closed condition or else the legs may be extended to support the basket 10 at a distance 20 above the floor when in their open condition as designated by reference character 28. In other words the basket may be placed in either a high position or a low position depending upon the condition of the cleats and legs.

Two tension springs 27 are mounted on the under side of the base 14 with their free ends connected to eyelets 26 mounted at the third edges 23 of the cleats 20, which are diagonally opposite the hinge mounting edges 21.

An opening means or elevating bar 30 is slidably mounted in guides 31 on each end portion 12 of the basket 10. The upper end of each elevating bar 30 has a laterally extending handle grip 34 that underlies its associated basket handle 13.

The lower end of each elevating bar is connected to the cleat eyelets 26 through curved elevating links 32. Each elevating link being pivotally secured to its associated elevator bar by means of a cotter pin 33.

Two tensioned latches 40 are mounted on the under side of the base 14. The latches are in the form of flat leaf springs that can be flexed from their anchorage points. Each latch 50 is offset at its midpoint 41 so that the free end of the latch lies in a plane below the fixed end of the latch. The free end of the latch is again offset to form a catch 42 having an abutment 43.

A closing means or retracting rod 50 is slidably engaged with guides 52 mounted on each

end portion 12 of the basket 10. The retracting rods are spaced from the elevating bars 30 and have handles or knobs 51 mounted on the upper ends thereof proximate the basket handles 13. The retracting rods 50 are attached to the free ends of the catches 42 by means of cotter pins 54 that pass through terminal holes 44 and 53 of the catches and retracting rods 42 and 50 respectively as is shown most clearly in the Figure 3.

When the legs are in their open condition as illustrated in the Figures 1, 3, 4 and 6 the lower face of each cleat 20 lays against the catch 42 with its second edge 22 engaged with the catch abutment 43. The abutments 43 lock the cleats in their open condition, as shown, wherein the basket member 10 is held in a raised position upon the legs 28. To fold the legs, the basket is raised slightly above the floor by its handles 13 and while the handles are being thus held by the hands the thumbs are used to depress the knobs 51 of the retracting rods 50. This causes the latches 40 to travel downward thereby disengaging the catches 42 from the cleats 20. This action leaves the cleats free to pivot on their hinges 25. The retraction springs 27 then pull the cleats into their closed condition as indicated by reference character 20a and the legs 28 assume their folded condition as indicated by the reference character 28a. The knobs 51 are then released and the latches 40 now having the position indicated by reference character 40a spring upward to lock the third edges 23 of the cleats 20 against the abutments 43 of the catches 42 wherein the cleats are in the position indicated by the reference character 20a. The abutments 43 are so shaped that the cleats 20 are held at a slight angle to the base 14 wherein the legs 28a are also slightly dependent to the plane of the base 14. The legs 28a are thus held below dead center and are locked in their position by the catches 42. Since the catches lock the legs 28a in their closed condition the coil springs 27 need only have enough strength to pull the cleats and legs into their closed condition after which the latches 40 hold them in place against up and down movement. Therefore the coil spring 27 may be a much weaker spring than would be required if it had to also hold the legs in their folded condition against the pull of gravity.

As will be seen from a study of the Figures 5 and 7 the pair of legs are so positioned on their respective cleats that they do not interfere with one another when in their folded condition.

To return the legs to their open condition the basket handles are again grasped by the hands while at the same time the elevating bar handles 34 are gripped by the finger tips and pulled up. The bars 30 and the elevating links 32 travel upward causing the cleat edges 23 to move outward and away from the catch abutments 43 against the pull of the coil springs 27. The handles 34 are pulled upward until the second edges 22 of the cleats 20 are again engaged with the catch abutments 43, as shown in the Figures 1, 3 and 6. The catches 42 will then hold the cleats 20 locked in their open condition.

Since the handles 34 need only be moved through a distance of approximately two inches and since our principle of construction permits the coil springs 27 to be relatively weak, a basket having a folding support made in accordance with this invention can be easily operated by a woman having average strength and length of finger grip. Furthermore, the releasing mech-

anism requires but slight thumb pressure on the two knobs 51 to cause the legs to retract under the action of the coil springs 27. The easy operation of this device is further brought about by the fact that the abutments 43 hold the cleats and legs below dead center when folded. Much less force is therefore required to initiate the opening cycle than is required by prior art devices whose legs are at or above dead center when folded.

It will now be clear that there is provided a device which accomplishes the objectives heretofore set forth. While the invention has been disclosed in its preferred form it is to be understood that the specific embodiment thereof as described and illustrated herein is not to be considered in a limited sense as there may be other forms or modifications of the invention which should also be construed to come within the scope of the appended claims.

We claim:

1. In combination, a laundry basket and a foldable support therefor, comprising a basket member including a base and two end portions, 25 a support member including two transversely extending cleats hingedly mounted on the said base, each of the said cleats having a pair of legs attached thereto, the said legs underlying the base when in a closed condition and depending from the base when in an open condition, two spring members mounted on the said base, each of the said springs having a free end connected to a cleat and constantly urging it into its closed condition, two tensioned latches mounted on the 30 said base, each of the said latches having a catch thereon capable of maintaining a cleat and the legs thereon in either of the said closed or open conditions, a closing means mounted on the two end portions and engaged with the said latches and capable of releasing the said catches to permit the spring members to move their respective cleats and legs into their closed condition, and an opening means mounted on the two end portions and engaged with the said cleats and capable of 35 temporarily disengaging the cleats from their respective catches and of moving the cleats and legs into their open condition.

2. In combination, a laundry basket and a foldable support therefore, comprising a basket member including a base and two end portions having handles mounted thereon, a support member including two transversely extending cleats hingedly mounted on the said base, each of the said cleats having a pair of legs attached thereto, the said legs underlying the base when in a closed condition and depending from the base when in an open condition, two spring members mounted on the said base, each of the said springs having a free end connected to a cleat and constantly urging it into its closed condition, two tensioned latches mounted on the said base, each of the said latches having a catch thereon capable of maintaining a cleat and the legs thereon in either of the said closed or open conditions, a closing means mounted on the two end portions proximate the said handles and engaged with the said latches and capable of releasing the said catches to permit the spring members to move their respective cleats and legs into their closed condition, and an opening means also mounted on the two end portions proximate the said handles and engaged with the said cleats and capable of temporarily disengaging the cleats from their respective catches and of moving the cleats and legs 40 into their open condition.

3. In combination, a laundry basket and a foldable support therefore, comprising a basket member including a base and two end portions, a support member including two transversely extending cleats, hingedly mounted on the said base, each of the said cleats having a pair of legs attached thereto, the said legs underlying the base when in a closed condition and depending from the base when in an open condition, each of the said cleats being substantially rectangular in cross-section and having three parallel edges, two spring members mounted on the said base, each of the said springs having a free end connected to a cleat and constantly urging it into its closed condition, two tensioned latches mounted on the said base, each of the said latches having a catch thereon engageable with one of the aforesaid edges when the cleats are in their closed condition and engageable with another of the said edges when the cleats are in their open condition, a closing means mounted on the two end portions and engaged with the said latches and capable of releasing the said catches to permit the spring members to move their respective cleats and legs into their closed condition, and an opening means also mounted on the two end portions and engaged with the said cleats and capable of temporarily disengaging the cleats from their respective catches and of moving the cleats and legs into their open condition.

4. In combination, a laundry basket and a foldable support therefore, comprising a basket member including a base and two end portions having handles mounted thereon, a support member including two transversely extending cleats hingedly mounted on the said base, each of the said cleats having a pair of legs attached thereto, the said legs underlying the base when in a closed condition and depending from the base when in an open condition, each of the said cleats being substantially rectangular in cross-section and having three parallel edges, two spring members mounted on the said base, each of the said springs having a free end connected to a cleat and constantly urging it into its closed condition, two tensioned latches mounted on the said base, each of the said latches having a catch thereon engageable with one of the aforesaid edges when the cleats are in their closed condition and engageable with another of the said edges when the cleats are in their open condition, a closing means mounted on the two end portions proximate the said handles and engaged with the said latches and capable of releasing the said catches to permit the spring members to move their respective cleats and legs into their closed condition, and an opening means also mounted on the two end portions proximate the said handles and engaged with the said cleats and capable of temporarily disengaging the cleats from their respective catches and of moving the cleats and legs into their open condition.

5. In combination, a laundry basket and a foldable support therefore, comprising a basket member including a base and two end portions, a support member including two transversely extending cleats hingedly mounted on the said base, each of the said cleats having a pair of legs attached thereto, the said legs underlying the base when in a closed condition and depending from the base when in an open condition, each of the said cleats being substantially rectangular in cross-section and having three parallel edges, two spring members mounted on the said base, each of the said springs having a free end connected

5 to a cleat and constantly urging it into its closed condition, two tensioned latches mounted on the said base, each of the said latches having a catch thereon engageable with one of the aforesaid edges when the cleats are in their closed condition and engageable with another of the said edges when the cleats are in their open condition, a closing means mounted on the two end portions and engaged with the said latches and capable of releasing the said catches to permit the spring members to move their respective cleats and legs into their closed condition, and an opening means also mounted on the two end portions and engaged with the third edge of the said cleats and capable of temporarily disengaging the cleats from their respective catches and of moving the cleats and legs into their open condition.

6. In combination, a laundry basket and a foldable support therefore, comprising a basket member including a base and two end portions, a support member including two transversely extending cleats hingedly mounted on the said base, each of the said cleats being substantially rectangular in cross-section and having three parallel edges, the said cleats being hingedly engaged with the said base at the first of the said edges, each of the said cleats having a pair of legs attached thereto, the said legs underlying the base when in a closed condition and depending from the base when in an open condition, two spring members mounted on the said base, each of the said springs having a free end connected to a cleat and constantly urging it into its closed condition, two tensioned latches mounted on the said base, each of the said latches having a catch thereon engageable with the third of the aforesaid edges when the cleats are in their closed condition and engageable with the second of the said edges when the cleats are in their open condition, a closing means mounted on the two end portions and engaged with the said latches and capable of releasing the said catches to permit the spring members to move their respective cleats and legs into their closed condition, and an opening means also mounted on the two end portions and engaged with the third of the aforesaid edges of the said cleats and capable of temporarily disengaging the cleats from their respective catches and of moving the cleats and legs into their open condition.

7. In combination, a laundry basket and a foldable support therefore, comprising a basket member including a base and two end portions, a support member including two transversely extending cleats hingedly mounted on the said base, each of the said cleats having a pair of legs attached thereto, the said legs underlying the base when in a closed condition and depending from the base when in an open condition, two spring members mounted on the said base, each of the said springs having a free end connected to a cleat and constantly urging it into its closed condition, two tensioned latches mounted on the said base, each of the said latches having a catch thereon capable of maintaining a cleat and the legs thereon in either of the said closed or open conditions, each of the said catches having abutments causing the pairs of legs to be non-parallel when in their closed or open condition, a closing means mounted on the two end portions and engaged with the said latches and capable of releasing the said catches to permit the spring members to move their respective cleats and legs into their closed condition, and an opening means

also mounted on the two end portions and engaged with the said cleats and capable of temporarily disengaging the cleats from their respective catches and of moving the cleats and legs into their open condition.

8. In combination, a laundry basket and a foldable support therefore, comprising a basket member including a base and two end portions having handles mounted thereon a support member including two transversely extending cleats hingedly mounted on the said base, each of the said cleats being substantially rectangular in cross section and having three parallel edges, the said cleats being hingedly engaged with the said base at the first of the said edges, each of the said cleats having a pair of legs attached thereto, the said legs underlying the base when in a closed condition and depending from the base when in an open condition, two spring members mounted on the said base, each of the said springs having a free end connected to a cleat and constantly urging it into its closed condition, two tensioned latches mounted on the said base, each of the said latches having a catch thereon en-

gageable with the third of the aforesaid edges when the cleats are in their closed condition and engageable with the second of the said edges when the cleats are in their open condition, each of the said catches having abutments causing the pairs of legs to be non-parallel when in their closed or open condition, a closing means mounted on the two end portions proximate the said handles and engaged with the said latches and capable of releasing the said catches to permit the spring members to move their respective cleats and legs into their closed condition, and an opening means also mounted on the two end portions, proximate the said handles and engaged with the third of the aforesaid edges of the said cleats and capable of temporarily disengaging the cleats from their respective catches and of moving the cleats and legs into their open condition.
